United States Patent Office

Des. 179,097
Patented Oct. 30, 1956

179,097

EVENING BAG OR SIMILAR ARTICLE

Florence K. Smith, Charleston Heights, S. C., assignor to Kono Manufacturing Co., Inc., Woodside, N. Y., a corporation of New York

Application January 19, 1956, Serial No. 39,845

Term of patent 14 years

(Cl. D87—3)

Fig. 1 is a perspective view of an evening bag or similar article showing my new design;

Fig. 2 is an end view thereof;

Fig. 3 is a perspective view of the evening bag in its unfolded position; and

Fig. 4 is a perspective view similar to Fig. 3 showing the cosmetic compartment in its open position.

I claim:

The ornamental design for an evening bag or similar article, as shown.
